CLAIM

The ornamental design for an aircraft, as shown and described.

DESCRIPTION

FIG. 1 is a top, rear, isometric view of an aircraft showing our new design.

FIG. 2 is a left side view thereof, the right side view being a mirror image thereof.

FIG. 3 is a top plan view thereof.

FIG. 4 is a rearward looking cross-sectional view thereof, taken along line 4—4 of FIG. 1;

FIG. 5 is a frontward looking cross-sectional view thereof, taken along line 5—5 of FIG. 1; and,

FIG. 6 is a left side view of an exterior thereof, the right side view of the exterior being a mirror image thereof.

The broken line shown in the figures is included for the purpose of illustrating environment and forms no part of the claimed design.
